FULL HOLE CASING OR TUBING HEAD

James Conn O'Neal, Beaumont, Tex., assignor to
Gulf Coast Machine & Supply Company, a corporation

Application July 16, 1936, Serial No. 90,831

13 Claims. (Cl. 285—22)

My invention relates to a well head construction to be used on casing or on tubing as the case may be.

It is an object of the invention to provide a head for use on casing or tubing which provides a full cylindrical opening therethrough for the performance of drilling and setting operations and which has no obstruction therein to hamper the operation of drilling, setting pipe and the like.

It is a further object, in connection with a full hole structure of this character, to provide an adjustable support for the inner concentric casing or tubing which is to be hung in the head.

It is an object of the invention to provide a support or hanger for the inner pipe which may normally remain in a retracted position so that the operations of drilling or completing of the well may be performed without interference, but which may be advanced into position to support the inner pipe whenever desired.

It is a further object of the invention to provide a supporting device of this character which is easily and positively operated from retracted to advanced position uniformly and with a minimum of effort.

It is a further object of the invention to provide a supporting device of the character stated which will be latched in either operative or inoperative position.

It is a further object of the invention to provide a head of the character stated upon which other operative devices such as valves and blow-out preventers may be mounted, but which may be reduced in diameter when the inner pipe has been hung in position so that further operations may be performed through a pipe of smaller diameter.

I desire to provide a head for the casing which, when an inner pipe or casing has been hung therein, may be dismantled so as not to interfere with further operations therein in connection with the inner string of pipe.

The invention lies largely in the particular construction and arrangement of the parts which make up my improved well head, which structure will be more fully explained in connection with the drawings herewith.

In the drawings Fig. 1 is a side view, partly in elevation and partly in vertical section showing a casing head embodying my invention equipped with well control apparatus thereon.

Fig. 2 is a view similar to Fig. 1 but showing the control apparatus removed and an inner string of pipe supported therein.

Fig. 3 is a broken sectional detail illustrating the sealing means employed with the inner pipe.

Fig. 4 is a transverse section on the plane 4—4 of Fig. 2.

Fig. 5 is a similar transverse section on the plane 5—5 of Fig. 1.

Fig. 6 is a broken section on the plane 6—6 of Fig. 5.

Fig. 7 is a broken side elevation of the housing for the operating stem.

Fig. 8 is a broken sectional detail showing the inner face of the operating device in latched position.

Fig. 9 is a similar view showing the latch in open position.

While it is understood that my invention may be employed for use upon either a casing or tubing I have illustrated the same in this invention as applied to a casing 1 which may be understood as extending down into the well for the desired distance. Upon this casing is mounted a casing head 2 constructed in accordance with my invention and having its upper end threaded with a coarse thread on its outer surface at 3 for engagement with a removable adapter ring 4. Said ring 4 when mounted upon the casing head forms a flange projecting radially from the upper end of the head and is formed with longitudinal openings 5 therethrough to receive bolts 6 by means of which the casing head may be connected to an upper ring 7, which serves to clamp upon the casing head an adapter 8 which will be later described.

The upper extremity of the casing head 2 is formed to seal with the adapter 8 and has an annular ridge 9 thereon to fit within the corresponding groove at the lower end of the adapter 8 and to compress packing 10 in said groove, thus forming a sealing contact. There is also a row of removable studs or pins 11 mounted in the upper end of the head and projecting upwardly therefrom in a position spaced slightly from the inner periphery of the head. These studs are for attachment with a subsequent device such as a packing gland or other means as will be later noted.

On the interior periphery of the casing head and at a level about midway between the ends thereof I form a radially extending groove 12 within which a set of hanging dogs may normally be housed. As will be seen particularly from reference to Fig. 5, this groove is deep enough to receive the dogs 13, which are housed therein, said dogs when in normal position having their in-

ner faces flush with the inner face of the casing head.

The dogs 13 are arcuate in shape and when in retracted position, as shown in Fig. 5, fit closely against the inner wall of the groove 12 in which they are housed. The dogs are comparatively short in length and a sufficient number are employed to entirely fill the groove except for an operating space or chamber 14 at one side of the casing head. Each dog is linked to the adjacent dog by connecting links 15. Said links are arcuate in shape and are fitted into grooves 16 in the outer side of each dog. A pivotal connection with the two dogs adjacent thereto is made by pins 17 extending through the link and the adjacent sides of the dogs. The inner side of each link 15 is spaced slightly from the lower side of the groove 16 in the dog so as to allow a certain amount of articulation between adjacent dogs to permit of the flexibility necessary in moving from retracted position, as shown in Fig. 5, to the advanced position shown in Fig. 4. As will be noted the grooves 16 in the dogs do not extend entirely across the two dogs 13a and 13b adjacent the operating mechanism. The groove is beveled outwardly and the end of the dog is rounded off to fit within the space provided.

A chamber 14 is formed at one side of the casing head within the channel of the groove 12. At that point the casing head is provided with an outwardly extending boss 17 and a threaded opening 18 is formed at that point. Within this threaded opening is fitted a sleeve 19, which acts as a support for an operating stem 20, which extends back axially through the sleeve. The sleeve is threaded at its inner end to engage within the opening 18 and is also threaded at its outer end at 21 to engage with a cap 22 as shown in Fig. 2.

The outer end of the sleeve is unobstructed but on the inner ends thereof the sleeve is closed except for an opening through which the operating stem 20 may pass. A stuffing box is formed within the sleeve about the stem 20, as shown at 23, to form a seal about the stem but permitting its rotation as will be later noted. The inner end of the stem has a radial flange 24 thereon. Extending inwardly from the flange 24 is a squared head 25.

The squared head fits within an operating disc 26 the construction of which may be seen in Figs. 8 and 9. Said disc fits slidably upon the end of the operating stem but is rotated through the rotation of the stem, as will be obvious. Although this slidable connection is shown as including a squared end for the disc, obviously a keyed connection could be used. The operating disc has at two points thereon an attachment for operating arms 27. Said arms are connected to the disc by means of screws 28, which allows the pivoting of the arms 27 thereon. The opposite end of each arm 27 is connected by means of the link 29 with the end of the adjacent dog 13a or 13b. This link forms a pivotal and flexible connection between the arms 27 and the dogs which is designed so as to allow a certain amount of play during the operation of the device.

As will be seen from Figs. 8 and 9, the arms 27 are arranged so that when the dogs are to be drawn together in supporting position the links 29 will interfit. When this is done the pivotal connection 30 of the link 29 with the dog will be aligned with the pins 28 on the dogs so that a toggle effect is obtained which tends to hold the dogs in position so that they cannot be moved apart. This will be understood from Fig. 8.

When the disc 26 is rotated to push the dogs away from the disc and move them into retracted position, as shown in Figs. 5 and 9, the pivotal points at both ends of the operating arms 27 and the disc will be again aligned so that a similar toggle effect is obtained, tending to hold the dogs in retracted position.

In the movement of the dogs I provide laterally extending pins 31 on each dog which project upwardly from the upper side of the dogs and move within an undercut groove 32 and limit the movement of the dogs inwardly. These pins 31 are wedge shaped with the apex extending inwardly and are thus formed so that if sand or other material packs within the groove the wedge shaped contour of each of the pins will tend to displace the packed sand or other material and allow the dogs to move to supporting position. In order to further assure the cleaning of the groove or recess 16 in the outer faces of the dogs and keep sand from packing therein I provide one or more openings 33 in the groove 12 in the casing head, these openings being normally closed by threaded plugs 34 which may be removed to provide attachment for a grease gun or other similar device through which fluid may be caused to flow around through the groove and displace the sand or other material. A steam jet may also be used.

In the rotation of the stem 20, I provide a laterally extending arm 35 which may be screwed diametrically through the stem. The ring or collar 36 fitting about the stem furnishes a bearing for the outer end thereof within the sleeve. The arm 35 extends through a slot 37 shown in Figs. 1 and 6, formed in the outer end of the sleeve 19. Said slot extends about 180° around the sleeve and at each end of said slot is formed an inwardly tapered opening 38, which forms a recess to receive a tapered latch member 39 formed upon the arm 35. As will be seen from Fig. 5, the latch 39 fits slidably over the arm 35 and has a sleeve 40, which acts as a housing around the arm 35 for a spring 41 which fits between the head 42 upon the arm 35 and the latch member 39. It will be seen that when this arm 35 is to be operated the operator will grasp the sleeve 40 and pull it radially outward to release the latch 39 from the recess 38. The arm may then be swung around in the slot 37 to the other end of its movement where the spring will force the latch 39 into the recess 38 in the opposite position of the supporting member.

With reference again to Figs. 1 and 2, during the drilling of the well through the casing head and the casing there will normally be above the casing head control equipment for the control of the well under pressure. It is often found that when the drill passes through formation containing gas that danger of blowout is present at all times and the drilling is performed with apparatus at the well head ready to close in the well in case a blowout is imminent. In my device is provided an adapter 8, previously noted, for attachment to the upper end of the casing head. This adapter is employed to connect the casing head with the lower end 43 of a master valve or blowout preventer or similar equipment which may be placed at the upper end of the casing head. The lower end of the adapter 8 is recessed on its inner side to provide space for the upwardly projecting studs or bolts 11. This recess thus provided is closed on its inner face by a sleeve 44, which fits at its upper end against a shoulder 45 on the interior of the adapter and

at its lower end rests upon the upper end of the casing head. It will be seen that when the adapter is clamped tightly against the casing head the sleeve 44 will be held rigidly in position 5 closing the interior of the adapter and forming a smooth and full opening downwardly through the adapter and casing head.

On the lower end of the adapter is a short outwardly extending flange 46 which provides an 10 upper shoulder to engage with the ring 7 previously noted. This ring will have spaced openings to receive the bolts 6 by means of which the ring may be bolted to the flange 4 of the casing head. When the nuts have not been clamped 15 tightly to engage the adapter with the casing head it will be seen that the ring or flange 7 on the adapter may be rotated with the ring 4 on the casing head to allow the ring 4 to be screwed on or off the head as desired. When the nuts 20 are tightened upon the bolt 6 the adapter and the casing head will be clamped rigidly together as is common in flanged connections thus forming a seal. At the upper end of the adapter 8 is a flanged connection 47 or any preferred alternative type of construction which needs no specific 25 description.

When the condition of the well necessitates the hanging of an inner string of casing or tubing within the casing head, the said inner string 30 which is shown at 48 in Fig. 2 is lowered downwardly into the well. The master valve and blow-out preventer will be in position to guard against a blowout at any time during this operation.

When the inner string is being set, and the 35 length of the pipe to be used is ascertained, the upper end of the string 48 is equipped with a special coupling 49 threaded for engagement with a pull nipple 50 or other connection. The inner string 48 is then ready for setting and may be swung 40 from dogs 13 or from casing elevators while being cemented. Control equipment and adapter 8 may be removed from the head when cement has set or can be removed after well has been completed. On its outer side the coupling 49 has a 45 radial flange 51 above and below which packing may be arranged to form a seal between said coupling and the inner wall of the casing head. At the lower end of the sleeve the outer diameter of the coupling is decreased to form a downwardly 50 presented shoulder 52 and at the lower end of the coupling is threaded exteriorly to attach a ring 53 which forms a stop member or support for a ring 54 above which the packing rings 55 are mounted. The supporting ring 54 is normally attached to the outer surface of the coupling by a 55 shear pin 56 shown best in Fig. 3. When in this position the supporting ring 54 rests upon the stop ring 53 and has above it the packing rings 55. The ring 54 is adapted to be moved upwardly to 60 compress the packing rings 55 when the weight of the inner casing string 48 is supported on the ring 54. When this is done the pin 56 is broken or sheared off and the ring is moved upwardly to compress the packing.

Above the flange 51 are packing rings 57 upon 65 which may be fitted a gland 58 whereby said packing may be compressed. The gland 58 has a laterally extending flange through which the studs or bolts 11 may extend. Upon this flange I place 70 a ring 59 also provided with openings to fit over the studs 11 and nuts 60 are then employed to compress the gland against the packing so as to form a seal at that point.

In setting the inner string, it will be understood 75 that the upper end of string 48 has been cut off

and threaded at approximately the correct position for hanging. The coupling is placed thereon together with the sealing rings 55 and the support therefor. When it is desired to hang the same after casing 48 has been cemented at the bottom 5 the lift nipple 50 is employed to pull upwardly and exert a stretch upon the string of pipe 48 and bring the lower end of the coupling 49 into position above the hanger dogs. The post or stem 20 is then rotated to throw the hanger dogs inwardly 10 into the position shown in Figs. 2 and 4, thus forming a supporting shoulder upon which the coupling may be lowered. When this is done the weight of the inner string upon the pipe will tend to force the ring 54 upwardly into position shown 15 in Fig. 2, thus compressing the packing rings 55 and forming a seal. When this portion of the hanging is done the arm or pin 50 which operates the stem 20 may be unscrewed and pulled outwardly and released from the said stem. A 20 cap such as is shown in Fig. 2 at 22 may then be screwed over the end of the same forming a closure around the stem and leaving the pipe properly supported on the dogs 13.

I then unscrew the threaded ring 4 from the 25 casing head, insert the packing rings 57, and place the gland 58 upon the packing rings 57 and tighten the gland in place so as to hold the said rings 57 in sealing position.

The pull nipple 50 may be unscrewed and a 30 bell nipple or other protecting means may be screwed therein so that drilling or other operations may proceed through the inner string 48. If it is desired to set a casing head upon the inner 35 upper end of the coupling 49, said casing head being equipped with my improved form of hanger if desired.

It will be noted that my hanger is particularly 40 desirable for handling the equipping of wells under pressure. The upper end of the well may be sealed by means of blowout preventers or other devices, allowing the pipe to be manipulated through said blowout preventer or other devices and through the head in the setting thereof and 45 when it is ready to support the pipe it may be properly supported upon the coupling 49, which is insertable downwardly through the control equipment and head without endangering a blowout. When the coupling 49 is in place the inner 50 string may be stretched and the hanging operation performed without difficulty. I provide a strong and efficient hanger which normally is out of the way and does not interfere with operations in the well but which can be easily advanced 55 to supporting position by the simple rotation of the operating stem. The further advantages of my invention will be obvious to those skilled in the art.

I claim:

1. A well head of the character stated including a tubular body threaded to engage a casing and having a full hole cylindrical interior, means at the upper end thereof for attachment to control equipment, an interior annular groove, supporting dogs housed in said groove, said dogs being linked together, and means operable from the exterior of said body to move said dogs to and from position projecting into said cylindrical interior to form a support for an inner pipe.

2. A well head of the character stated including a tubular body threaded to engage a casing and having a full hole cylindrical interior, means at the upper end thereof for attachment to control equipment, an interior annular groove, sup-

60

65

70

75

- porting dogs housed in said groove, said dogs being linked together, a rotatable stem having a sealing engagement through the wall of said head and means connecting the inner end of said stem with said dogs whereby the rotation of said stem will move said dogs inwardly to supporting position or outwardly to a position housed in said groove.
3. A well head of the character stated including a tubular body threaded to engage a casing and having a full hole cylindrical interior, means at the upper end thereof for attachment to control equipment, an interior annular groove, supporting dogs housed in said groove, said dogs being linked together, a rotatable stem having a sealing engagement through the wall of said head and means connecting the inner end of said stem with said dogs whereby the rotation of said stem will move said dogs inwardly to supporting position or outwardly to a position housed in said groove, and means to latch said stem against rotation.
4. In a well having therein a plurality of concentric strings of pipe, an outer casing, a casing head thereon, an adapter on said casing head to connect control equipment thereto, a ring having threaded attachment on the exterior upper end of said head to form a flange thereon, an upwardly presented shoulder adjacent the lower end of said adapter, a ring fitting above said shoulder, means connecting said rings together, sealing means between the adjacent ends of said head and adapter, and means in said casing head to support an inner string of pipe.
5. In a well having therein a plurality of concentric strings of pipe, an outer casing, a casing head thereon, an adapter on said casing head to connect control equipment thereto, a ring having threaded attachment on the exterior upper end of said head to form a flange thereon, an upwardly presented shoulder adjacent the lower end of said adapter, a ring fitting above said shoulder, bolts extending through said rings to clamp said adapter to said head, said rings being rotatable simultaneously when screwing said threaded ring on said head.
6. A casing head having a cylindrical passage therethrough, an inner groove in said head extending horizontally about the passage, a plurality of dogs normally housed in said groove, a stem extending through the wall of said head into said groove, a disc-shaped head on said stem, and links pivotally connected to said head and to said dogs to move said dogs inwardly and outwardly in said groove as said stem is rotated.
7. A casing head having a cylindrical passage therethrough, an inner groove in said head extending horizontally about the passage, a plurality of dogs normally housed in said groove, a stem extending through the wall of said head into said groove, a disc-shaped head slidably mounted on said stem, and links pivotally connected to said head and to said dogs to move said dogs inwardly and outwardly in said groove as said stem is rotated, the pivotal connections on said links being aligned in both inward and outward positions of said dogs.
8. A casing head having a cylindrical passage therethrough, an inner groove in said head extending horizontally about the passage, a plurality of dogs normally housed in said groove, said dogs being linked together to allow limited pivoting movement between adjacent dogs, an operating disc, two of said dogs being operatively connected with said disc whereby the rotation of said disc will move said dogs.
9. A casing head having an inner passage, an annular groove in the wall of said passage, arcuate dogs normally housed in said groove, links connecting all but two of said dogs, a disc to which said two dogs are connected, a stem on said disc, and means to rotate said stem and disc to move said dogs in said groove.
10. A casing head having an inner passage, an annular groove in the wall of said passage, arcuate dogs normally housed in said groove, links connecting all but two of said dogs, a disc to which said two dogs are connected, a stem on said disc, means to seal about said stem, a latch on said stem.
11. A casing, a casing head thereon having a passage having approximately the same diameter as said casing, an annular groove on the inner surface of said head, arcuate dogs housed in said groove, an inner pipe, a coupling at the upper end thereof, a radial flange thereon fitting within said head, packing means below said flange, a ring below said packing means adapted to seat upon said dogs when said dogs are advanced inwardly and means to move said dogs positively into and out of said passage to support said inner pipe operative from the exterior of said head, the weight of said pipe acting to compress said packing.
12. A casing, a casing head thereon having a passage having approximately the same diameter as said casing, an annular groove on the inner surface of said head, arcuate dogs housed in said groove, an inner pipe, a coupling at the upper end thereof, a radial flange thereon fitting within said head, packing means below said flange, a ring below said packing means adapted to seat upon said dogs when said dogs are advanced inwardly and means to move said dogs positively into and out of said passage to support said inner pipe operative from the exterior of said head, the weight of said pipe acting to compress said packing, and means above said flange to seal between said coupling and said head, said last named means also acting to resist upward movement of said pipe.
13. A well casing, a casing head thereon having an inner cylindrical passage, an inner pipe, well control equipment above said casing through which said pipe may be moved vertically, a coupling on said pipe, a flange on said coupling fitting within said casing head, seal rings below said flange, a supporting ring for said seal rings below the same, and means operative from the outside of said casing head adapted to be positively moved inwardly or outwardly below said supporting ring to support or release said pipe when desired.

JAMES CONN O'NEAL.
